UNITED STATES PATENT OFFICE.

THOMAS SINGLETON, JR., OF NEW BEDFORD, MASSACHUSETTS, ASSIGNOR
TO THE MOUNT WASHINGTON GLASS COMPANY, OF SAME PLACE.

DESIGN FOR AN ORNAMENTAL GLASS DISH.

SPECIFICATION forming part of Design No. 22,169, dated January 31, 1893.

Application filed September 16, 1892. Serial No. 446,109. Term of patent 7 years.

To all whom it may concern:

Be it known that I, THOMAS SINGLETON, Jr., of New Bedford, in the county of Bristol and State of Massachusetts, have invented and 5 produced a new and original Design for Glassware, of which the following is a specification, reference being had to the accompanying drawings, illustrating the same and showing it embodied in a glass dish or shallow bowl. 10 Figure 1 is a plan of a dish containing my new design and Fig. 2 is a cross-sectional view of the same.

My design consists in a series of indentations radiating from the center of the dish 15 and a series of horse shoe shaped indentations, the apices of which are near the rim of the dish. These indentations cross each other and form fields which are ornamented in various ways.

20 *a a'* are the indentations radiating from the

middle of the bottom of the dish and *b b' &c.* are the horse shoe shaped indentations whose apices *b b'* are near the rim of the dish. The indentations *b b'* cross at *f*, and there are other indentations *g g'*, which form a series 25 of loop like fields which extend from the middle of the dish upward near its rim. The outer portions of the horse shoe shaped figures are decorated with stars 1, 2, 3, 4 &c., and the dish is otherwise ornamented. But the 30 distinguishing characteristic of my design consists in the intersecting horseshoe shaped fields caused by the indentations referred to.

What I claim is:

The design for an ornamented glass dish 35 as herein described and shown.

THOMAS SINGLETON, Jr.

Witnesses.
